UNITED STATES PATENT OFFICE.

EDMUND A. STRAUSE, OF LOS ANGELES, CALIFORNIA.

DESIGN FOR A GLASS-HOLDER.

42,425.

Specification for Design.

Patented Apr. 23, 1912.

Application filed December 4, 1911. Serial No. 663,959. Term of patent 7 years.

To all whom it may concern:

Be it known that I, EDMUND A. STRAUSE, a citizen of the United States, residing at Los Angeles, in the county of Los Angeles and State of California, have invented a new, original, and ornamental Design for Glass-Holders, of which the following is a specification, reference being had to the accompanying drawing, forming part thereof.

The figure is a perspective view of a glass holder, showing my new design:

I claim:

The ornamental design for a glass holder as shown.

EDMUND A. STRAUSE.

Witnesses:

EARLE R. POLLARD,
MARGARET STRAUSE.
